UNITED STATES PATENT OFFICE

149,576

DESIGN FOR A WHEEL COVER OR THE LIKE

George Albert Lyon, Detroit, Mich.

Application May 6, 1947, Serial No. 138,841

Term of patent 14 years

(Cl. D14—30)

To all whom it may concern:

Be it known that I, George Albert Lyon, a citizen of the United States and a resident of the city of Detroit, in the county of Wayne and State of Michigan, have invented a new, original, and ornamental Design for a Wheel Cover or the Like, of which the following is a specification, reference being had to the accompanying drawing, forming a part thereof.

On the drawing:

Figure 1 is a side view of my novel design for wheel cover showing in dotted lines a wheel assembly to which the design is adapted to be applied.

Figure 2 is a diametric sectional view of the wheel cover indicating in broken outline, for illustrative purposes only, a wheel and tire with which the cover may be associated.

Figure 3 is an enlarged fragmentary cross sectional view through a portion of the wheel cover showing more clearly its contours.

I claim:

The ornamental design for a wheel cover or the like, as shown and described.

GEORGE ALBERT LYON.
